UNITED STATES PATENT OFFICE.

LOUIS B. PRAHAR, OF NEW YORK, N. Y.

SAFETY-RAZOR.

No. 922,188.

Specification of Letters Patent. Patented May 18, 1909.

Application filed March 16, 1908. Serial No. 421,412.

To all whom it may concern:

Be it known that I, LOUIS B. PRAHAR, a citizen of the United States, and a resident of the city of New York, borough of Brooklyn, in the county of Kings and State of New York, have invented a new and Improved Safety-Razor, of which the following is a full, clear, and exact description.

This invention relates to certain improvements in safety razors, and more particularly to the means employed for supporting the cutting blade.

In safety razors of the type to which mine belongs, it is customary to provide a blade-supporting member formed of sheet metal and having means integral with said member or rigidly secured thereto, for holding the blade in the desired position.

The object of my invention is to provide a plate with which the blade has sliding engagement, and having end guides or lugs to hold the blade in engagement with the plate as the latter is slid into place, stops to limit the forward movement of the blade, and a spring movable below the plane of the plate and adapted to automatically lock the blade against return movement when said blade reaches the desired position.

Reference is to be had to the accompanying drawings, forming a part of this specification, in which similar characters of reference indicate corresponding parts in all the figures, and in which—

Figure 1 is a perspective view of one form 35 of safety razor constructed in accordance with my invention; Fig. 2 is a transverse section, said section being taken on the line 2—2 of Fig. 3; Fig. 3 is a plan view of the blade-supporting plate; Fig. 4 is a plan view 40 of the blade-supporting plate and cutting blade, and showing a slightly modified form of retaining spring; and Fig. 5 is a section similar to Fig. 2, but taken on the line 5—5 of Fig. 4.

In the drawings I have illustrated a blade-supporting plate having a handle 10 integral therewith at the rear edge thereof, but it is evident that the blade-supporting plate may be supported and held in any suitable manner and by any suitable form of handle.

In the specific form illustrated in Figs. 1, 2 and 3, the blade-supporting plate 11 is provided at the front edge thereof with a plurality of slots separating the edge of the plate 55 into a plurality of teeth 12, constituting a

guard or comb. The plate is substantially flat and at the opposite ends thereof, I provide substantially U-shaped slots 13, which define two sets of lugs 14 integral with the body of the plate. The lugs are stamped up, so that the larger portions thereof lie in a plane substantially parallel to the plate and spaced therefrom a distance substantially equal to the thickness of the cutting blade. The distance between the outer end of one slot and the outer end of the other is substantially equal to the length of the cutting blade, so that the lugs 14 serve not only to hold the blade in engagement with the plate but also prevent longitudinal movement thereof.

At the front edge of the plate and adjacent the ends of the comb or guard, I provide two projections or lugs 15, constituting stops for limiting the forward movement of the blade. These stops are so placed that they engage with the cutting edge of the blade adjacent the corners thereof, so as to protect said corners, as well as to limit the forward movement of the blade. At the rear edge of the plate I provide a spring 16, which is formed integral with the plate and defined by a substantially U-shaped slot 17. The slot is of sufficient length, so that the tongue or spring may have the desired amount of resiliency, and said tongue or spring is stamped so as to normally extend slightly above the plane of the upper surface of the plate but be readily moved downward to a position below the plane of said upper surface.

In assembling the device, the blade 18, formed of thin steel, is placed directly over the spring and depressed to force the spring downward, so that it does not project above the surface of the plate. The blade is then moved forward while in engagement with the plate and is slipped under the two guides or lugs 14, and the forward movement continued until the front edge of the blade engages with the stops 15. At this time, the rear edge of the blade passes out of engagement with the spring 16, and the latter automatically snaps upward into engagement with the rear edge of the blade to hold the latter securely in place and prevent the return movement. The blade is held against forward movement by the stops 15, against endwise movement by the lugs 14, against rearward movement by the spring 16, and against movement away from the plate by

the lugs 14. All of these guides and stops are integral with the plate and may be stamped therefrom at a single operation.

To remove the blade, it is merely necessary to depress the spring 16 with the thumb nail and the blade may freely move rearwardly over the spring and the spring held depressed by the blade until the latter passes from under the lugs 14.

10 If the plate be made of a metal having but little resiliency, as, for instance, aluminum, I may, if desired, form the spring of a separate piece of metal, as illustrated in Figs. 4 and 5. In this case, the plate is provided 15 with an opening 17^a adjacent the rear edge thereof, and a spring 16^a is secured in any suitable manner to the under side of the plate. As shown, the spring has one end riveted and the opposite end extending upward through the opening 17^a and presenting a shoulder adapted to engage with the rear edge of the blade. Other forms of springs may be provided, it only being essential that the spring be so formed and disposed as to 25 be capable of depression below the plane of the upper surface of the plate, so as to permit the rearward sliding movement of the blade and to automatically rise into engagement with the rear edge of the blade after 30 the latter has been moved forward to the limiting position, that is, into engagement with the stops 15.

I am aware that safety razors have been designed in which stops are employed for 35 engagement with the corners of the blade at the cutting edge thereof, and also safety razors have been designed in which the blade might be removed laterally by sliding from beneath lugs or guides integral with the 40 plate and formed by bending over the edge thereof. By forming the guides of a portion of the plate stamped upwardly and bounded by a substantially U-shaped slot, I more easily adjust them to the thickness of the 45 blade and there is no liability of the lugs being broken off by bending them at such a sharp angle as is necessary when the edge of the plate is bent back upon itself to form the guide. By so forming the spring that it may 50 be depressed below the plane of the plate, the blade may be very readily removed upon the depression of the spring but it cannot become accidentally detached or dislocated.

Having thus described my invention, I 55 claim as new and desire to secure by Letters Patent:

1. In a safety razor, a blade-supporting member, a blade carried thereby, means for limiting the forward movement of said blade, 60 means for normally preventing the rearward movement of said blade, and guides for holding said blade in engagement with said member and beneath which said blade may slide to remove the same, each of said guides being 65 integral with said blade-supporting member

and formed of a portion of the body thereof stamped upwardly from the member intermediate its ends and lying in a plane substantially parallel to said member and spaced therefrom a distance substantially equal to 70 the thickness of the blade.

2. A safety razor, comprising a blade, a blade-supporting member, a handle therefor, guides adjacent the ends of said member for holding said blade in engagement with said member, stops for limiting the forward movement of said blade, and a spring for normally preventing the rearward movement of said blade, said blade-supporting member, handle, guides, stops and spring being stamped 75 from a single piece of sheet metal.

3. In a safety razor, a substantially flat blade-supporting member formed of sheet metal and having the front edge thereof constituting a guard, a handle at the rear edge of 85 said member, a flat blade of substantially uniform thickness and adapted to rest directly upon said member and having sliding engagement therewith, means for limiting the forward movement of the blade, guides 90 adjacent the ends of said member and lying in planes substantially parallel to said member and spaced therefrom a distance substantially equal to the thickness of the blade, and a spring adjacent said handle at the rear side 95 of said member and depressible to a position below the plane of the upper surface of said member and adapted to automatically snap into engagement with said blade to hold the latter in position after said blade has been 100 moved forwardly in contact with said member and to its limiting position.

4. In a safety razor, a substantially flat blade-supporting plate formed of sheet metal, a blade carried thereby and adapted 105 for sliding engagement therewith, stops integral with said plate for limiting the forward movement of said blade, guides integral with said plate and formed of a portion of the body thereof stamped upward from the plate intermediate its ends and lying in planes substantially parallel to said plate and spaced therefrom a distance substantially equal to the thickness of the blade, said plate having 110 an aperture therein adjacent the rear side thereof, and a spring adjacent said aperture and depressible to a position below the plane of the upper surface of the plate and adapted to rise through said aperture and automatically snap into engagement with the rear end 115 of the blade to hold the latter in position after said blade has been moved forwardly beneath said guides and into engagement with said stops.

5. A safety razor comprising a one-piece 125 sheet metal bar having one end bent at an acute angle to the main body and terminating in comb teeth forming a blade support, said blade support having its opposite edges formed with integral tongues bent toward 130

each other partially across the face thereof, the end teeth having portions thereof pressed up forming limiting stops for the cutting edge of the blade, and a blade inserted 5 between the tongues and adjacent portion of the blade support.

6. A safety razor comprising a one-piece sheet metal bar having one end bent at an acute angle to the main body and terminating in comb teeth forming a blade support, 10 said blade support having its opposite edges formed with integral tongues bent toward each other partially across the face thereof, the end teeth having portions thereof

pressed up forming limiting stops for the cutting edge of the blade, and a blade inserted between the tongues and adjacent portion of 15 the blade support, said bar having an integral spring tongue stamped therefrom and projecting forwardly over the upper edge of 20 the blade.

In testimony whereof I have signed my name to this specification in the presence of two subscribing witnesses.
